UNITED STATES PATENT OFFICE.

JESSEE MERCER WHITE, OF PHILADELPHIA, PENNSYLVANIA.

AUTOMOBILE LOCK.

Application filed May 22, 1923. Serial No. 640,688.

To all whom it may concern:

Be it known that I, JESSEE M. WHITE, a citizen of the United States, residing at Philadelphia, in the county of Philadelphia and State of Pennsylvania, have invented certain new and useful Improvements in Automobile Locks, of which the following is a specification.

My invention relates to automobile locks, 10 more especially to locks which may be termed automatic or fool-proof. In other words locks which require the driver to lock the automobile in order to stop the engine.

Heretofore it has been the practice to apply locks, for making and breaking the ignition circuit, in the wire which leads from the starter circuit and commonly known as the feed wire. These circuit breaking locks were always applied at a distance from the 20 starter circuit and thus left a part of the feed wire subjected to circuit shorting which burnt the wire and set fire to the automobile. The feed wire is always of small size, being required to carry small amperage 25 (5 to 25 amperes), while the starter circuit wire, to which the feed wire is connected is always of large size, being required to carry large amperage (80 to 400 amperes) for the 30 starter. It is apparent that in case a circuit is shorted the large wire will readily carry amperage to its full capacity and, if this amperage is resisted by a small wire, heat will be generated which will cause the feed wire to burn with danger of setting 35 fire to the automobile. Furthermore the starting circuit wire is long (6 to 12 feet), thus subjecting a large area to possibility of a short circuit.

The objects of my invention are to provide 40 means which will prevent the burning of the feed wire in case it is shorted, render the long starting circuit wire immune to circuit shorting, lock the ignition, lighting and starting systems, and means which will require the driver to lock the automobile in order to stop the engine.

These objects, and other advantageous ends which will be described hereinafter, I 50 attain in the following manner, reference being had to the accompanying drawings in which—

Figure 1 is a central section through an automobile lock constructed in accordance with my invention showing it applied to the transmission casing of an automobile,

Figure 2 a view similar to Figure 1 partly

in full illustrating the locking bolt in another position,

Figure 3 a section on line 3—3 of Figure 1 illustrating the electrical connections to the lock diagrammatically,

Figure 4 a view similar to Figure 3 taken on line 4—4 of Figure 2,

Figure 5 a section on line 5—5 of Figure 2, and

Figure 6 a section on line 6—6 of Figure 5.

Referring to the drawings, 1 indicates the transmission casing of an automobile, 2 the rotating member keyed to the driving shaft 70 3. The universal joint which leads to the differential, not shown, is connected to the rotating member 2 through holes 4. The rotating member has locking teeth 5 adapted to engage grooves 6 in a locking bolt 7 turnably mounted in an extension 8 of the casing. The bolt is held against vertical movement by a shank 9 which has a threaded end 10 for receiving a nut 11. The locking bolt is locked against rotation by any suitable 80 means but preferably by the mechanism shown at 12 which includes a locking drum 13 rotatable in the bolt and having recesses 14 adapted to receive balls 15 when in unlocked position. The balls rest in holes 16 85 in the bolt and engage depressions 17 in the casing when the drum is turned to force the balls out of recesses 14 to lock the bolt to the casing. The bolt is turned by any suitable knob, such as shown at 18, and extends 90 above the floor line 19 of an automobile.

A position finder which includes a ball 20 pressed by a spring 21 held in position by a screw 22 and which engages depressions 23 in the bolt finds the locked and unlocked position of the bolt while turning the same.

A recess 24 is formed in the periphery of the locking bolt and provides a space in which the contacting plungers of a circuit making and breaking device are disposed when the bolt locks the rotating member against rotation as shown in Figure 2. The circuit making and breaking device comprises a housing 25 insulated from the casing by a gasket 26 and secured to the casing by screws 27. The housing is provided with holes 28 for receiving spring-pressed plungers 29 which have a hollow part 30 for receiving springs 31. Each plunger is provided with a reduced solid part 32 which passes through a hole 33 in the gasket, the

hole being of a smaller dimension than the housing hole 28 so as to provide a shoulder 34 adapted to be engaged by the hollow part 30 of the plunger to limit its movement into the casing. The casing is provided with holes 35 through which the solid parts of the plungers pass without contacting with the casing. A terminal post 36 of any suitable character is provided on the housing to which is connected one end of a ground wire 37. The other end is connected to one pole of a battery 38. The starting system is connected, by a starter circuit wire 39, to the other pole of the battery and is grounded at 40. The ignition system is connected to the starter wire by a feed wire 41 and is grounded at 42. The lighting system is connected to the feed wire by a lead wire 43 and is grounded at 44. The locking bolt and casing are grounded as shown at 45.

With my lock applied when the engine is running the spring-pressed plungers are normally in engagement with the periphery 25 of the locking bolt, thus completing a circuit through the ground wire as shown in Figures 1 and 3. To stop the engine the driver must disconnect the ignition system and in doing so will turn the locking bolt 30 from the position shown in Figures 1 and 3 to the positions shown in Figures 2 and 4. This movement will bring the grooves 6 in engagement with the teeth of the rotating member 5 and the recess 24 opposite the 35 spring-pressed plungers. The recess 24 being deeper than the lengthwise movement of the plungers, the plungers will be disengaged from the locking bolt, and the circuit through the ground wire broken and 40 the engine stopped. The grooves 6 being in engagement with the teeth 5 of the rotating member, will lock the automobile against movement. The bolt is then locked to the casing by the lock 12 and the key removed. This locks the automobile against 45 movement and disconnects the electrical systems from the battery so that a short circuit with any of their wires is impossible because the ground connection is broken.

By constructing a lock and connecting it 50 with an electrical system of an automobile as above described, a lock is provided which must be locked in order to stop the engine and when locked the electrical systems are rendered immune to circuit shorting.

While I have described my invention as taking a particular form, it will be understood that the various parts of my invention 60 may be changed without departing from the spirit thereof, and hence I do not limit myself to the precise construction set forth, but consider that I am at liberty to make such changes and alterations as fairly come within the scope of the appended claims.

Having described my invention, what I

claim as new and desire to secure by Letters Patent is:—

1. In connection with the electric wiring system of an automobile, circuit breaking means in the ground wire connection; means 70 for locking the car against movement, and common means for actuating the circuit breaking means and the locking mechanism whereby cutting off the motive power automatically locks the car against movement. 75

2. In connection with the electric wiring system of an automobile, means for locking the car against movement, and spring-pressed plungers, electrically connected to the ground wire, normally in contact with 80 the locking means and adapted to be disengaged therefrom when the locking means are moved into locking position.

3. In connection with the electric wiring system of an automobile, means for locking the car against movement; a housing carried by and insulated from the locking means, and spring-pressed plungers within the housing, electrically connected to the ground wire, normally in contact with the 90 locking means and adapted to be disengaged therefrom when the locking means are moved into locking position. 95

4. In connection with the electric wiring system of an automobile, a casing carried by the automobile; a turnable bolt within the casing adapted to lock the automobile against movement; a housing carried by the casing and insulated therefrom, and spring pressed plungers within the housing, 100 electrically connected to the ground wire, normally in contact with the locking bolt but adapted to be disengaged therefrom when the locking bolt is moved into locking position. 105

5. In connection with the electric wiring system of an automobile, a casing carried by the automobile; a turnable bolt, having a recess and mounted within the casing, adapted to lock the automobile against movement; a housing carried by the casing and insulated therefrom, spring-pressed plungers within the housing, electrically connected to the ground wire, normally in contact with the locking bolt but adapted to take into the recess and to be disengaged from the locking bolt when the bolt is moved into locking position. 110

6. An automobile lock including a casing; a rotating member mounted on the casing; a turnable bolt within the casing adapted to lock the rotating member; a housing secured to the casing and having holes therein; a terminal on the housing; an insulating gasket between the casing and housing having holes therein of smaller dimension than the holes in the housing, and spring-pressed plungers taking through the holes in the housing, each plunger having a reduced part taking through a hole in the 120 125 130

gasket and normally in contact with the bolt but adapted to be disengaged therefrom when the bolt is moved into locking position.

5 7. An automobile lock including a casing; a rotating member mounted on the casing; a turnable bolt having a recess and adapted to lock the rotating member; a housing secured to the casing and having holes therein; a terminal on the housing; an insulating gasket between the casing and housing having holes therein of smaller dimension than the holes in the housing; springs within the housing, and plungers taking through the holes in the housing and having a hollow part for receiving the springs, each plunger having a solid reduced part taking through a hole in the gasket and normally in contact with the bolt but adapted to be within the recess and to be disengaged from the bolt when the bolt is 15 moved into locking position.

20 8. An automobile lock including a casing; a rotating member mounted on the casing; a turnable bolt having a recess and adapted

to lock the rotating member; a housing secured to the casing and having holes therein; a terminal on the housing; an insulating gasket between the casing and housing having holes therein of smaller dimension than the holes in the housing; springs within the housing, and plungers taking through the holes in the housing and having a hollow part for receiving the springs, each plunger having a solid reduced part taking through a hole in the gasket and normally in contact with the bolt but adapted to be within the recess and to be disengaged from the bolt when the bolt is moved into locking position.

25 30 35 In testimony whereof I have signed my name to this specification in the presence of 40 two subscribing witnesses.

JESSEE MERCER WHITE.
